UNITED STATES PATENT OFFICE

EARL D. TUBBS, OF NEW YORK, N. Y.

BOX STRAPPING APPARATUS

Application filed March 5, 1930. Serial No. 433,478.

This invention relates generally to an apparatus or device for strapping boxes or bales, or the like, and the improvements are directed to novel and unique means for ap-

plying, tensioning, twisting and severing the material, such as wire, used in strapping said boxes.

Primarily, the object of the present invention resides in the provision of a device of the above-mentioned character which is exceedingly compact, relatively light in weight, and which has its exposed operative parts arranged to preclude injury to the operator and which handles the material to be twisted in a manner to prevent bruising the hands of the manipulator of said device.

Another object is the provision of a gripping mechanism adapted to clinch one end of the wire in a manner to prevent slippage thereof during the tensioning or tightening of said wire around a bale or box, said mechanism being adapted to become more effective as the tension on the wire is increased.

Still another object of the invention is to provide novel automatic drop latch means, directly associated with said gripping mechanism, and adapted to secure the wires in juxtaposition and to maintain the same in this condition during the operation of the tensioning means and the twisting operation. Said latch means also facilitating the freeing of the twisted wire and removal of the device from a box or bale.

Still another object is to provide a tensioning or tightening mechanism, including certain operative parts whereby the wire attached thereto is prevented from slipping during the tightening operation.

A still further object of the invention resides in the provision of a novel clamping device, in the form of a star drum, said drum being operatively connected to said tensioning mechanism and adapted to positively maintain an intimate anti-slip relation between the same and the wire.

A still further object is to provide certain braking means which cooperates with certain rotative parts to prevent the operation thereof prior to the twisting of the wire and during

the placement of the wire into the device, said braking means also serving to stop the operation of the device, after the twisting operation.

Still another object of the invention is to provide a novel assemblage of parts adapted to be operated to twist the wire after it has been tensioned and suitably applied to a box or bale.

Another aim is to provide periodically operable mechanism, in the form of oscillatory arms, adapted to be operated to bring certain cutting means in proper spaced relation to sever the undesired ends of the twisted wire.

The invention is featured by the provision of certain cutting means which are borne by said oscillatory arms and which are adapted to cut off the wire at the terminals of the twisted portion thereof and to snugly bend said cut ends in close proximity to the wire.

Still another aim of the invention is to provide means whereby the twisting operation is continued sufficiently beyond the cutting operation in order that the ends of the wire may be bent up and down, respectively, and arranged in close relation to the uncut portions of the wire.

As will presently appear the invention is further featured by the provision of carrying means whereby a perfect balance may be maintained during the portage of the device; and further said device is adapted to handle wire from coils or pre-cut lengths thereof.

A subsidiary feature of the invention also is present in the form of a novel form of casing member adapted to completely inclose the operative parts of the device, and which is uniquely formed to render the device exceedingly compact, said casing being readily removable to expose the mechanism of the device and to permit removal or replacement of the parts thereof.

With these objects in view, together with others which will appear as the description proceeds, the invention resides in the novel formation, combination, and arrangement of parts, all as will be described more fully hereinafter, illustrated in the drawings, and particularly pointed out in the claim.

In said drawings:

Figure 1 is a front elevation of the device.

Fig. 2 is a rear elevation thereof.

Fig. 3 is a front elevation of the mechanism of said device, (slightly enlarged), the casing being sectioned and partly broken away at the right to expose a portion of the tensioning means.

10 Fig. 4 is an end elevation of the mechanism shown in Fig. 3, the casing being sectioned.

Fig. 5 is a vertical sectional view, taken substantially on the line 5—5 of Fig. 3.

15 Fig. 6 is a plan view of the mechanism with the casing removed.

Fig. 7 is a sectional view taken on the line 7—7 of Fig. 6 and showing the parts in the positions assumed just prior to the twisting operation.

20 Fig. 8 is a view like unto Fig. 7, but showing the positions of certain parts subsequent to the twisting and severing operations.

Fig. 9 is a sectional view, slightly enlarged, of the parts destined to twist the 25 wire, said section being taken substantially on the line 9—9 of Fig. 5.

Fig. 10 is an enlarged side elevation of the rotative element shown in Fig. 9.

20 Fig. 11 is a central sectional view thereof, taken on the line 11—11 of Fig. 10.

Fig. 12 is an end elevation of one of the tubular or barrel members shown in Fig. 9.

25 Fig. 13 is a sectional view of the rotative element and its cooperating barrel members and diagrammatically illustrating the twisted overlapping ends of the wire and the bent condition of the cut ends thereof.

40 Fig. 14 is a face view of the star drum showing diagrammatically the condition of the end of the wire clamped thereby after the tensioning operation.

45 Referring now more in detail to the accompanying drawings, wherein like characters of reference denote similar parts throughout the several views, let 1 denote a base, adapted to support substantially all the operative parts of the device, said base being provided with a pair of spaced standards 2 and 3, which are suitably bored to rotatively support a stub 50 shaft 4, the latter having a spur gear 5 pinned intermediate the ends thereof as shown at 6, in Fig. 6. The outer ends of said shaft 4 are each provided with hub 7 and 8, suitably splined thereto as indicated in Fig. 7, each 55 of said hubs being provided with a radial projection 9, adapted to periodically actuate certain oscillatory arms, bearing certain cutting elements, as will presently appear. Upon inspection of Figs. 3 and 7, it will be noted 60 that said base 1 is provided with an upstanding ear 10 and a block 11, the latter being clearly shown at the extreme left in Figs. 3 and 6, said ear and block being suitably apertured for the reception of screws 12 and 13 respectively, which are adapted to serve

as pivotal bearings for the ends of the oscillatory arms 14 and 15. Said oscillatory arms are somewhat similar in construction, each being provided with a forwardly directed block portion 16, (see Figs. 6 and 7) 70 having vertical bores 17 and lateral bores 18, intercommunicating, said vertical bores being adapted to receive cutters 19 and 19a, the former being associated with the oscillatory arm 15 and the latter with the oscillatory arm 16, as shown in Fig. 3. Said cutters may be adjusted vertically by operating a set screw 20 in each of said blocks 16, while set screws 21 serve to bind said cutters in their proper adjusted condition. 75

80 As shown in Figs. 5 and 6, said base 1 is also provided with a block 22 which extends forwardly of the front edge of said base and intermediate the length thereof, and which rises upwardly to define projections 23 and 24 having a space therebetween for the partial reception of said spur gear 5. The details of said block 22 will be readily understood upon reference to Fig. 9, wherein it will be noted that the same is provided with bores 25 and 26, coaxially arranged and leading into the opening 27 which latter receives a rotative element 28 enmeshed with spur gear 5, and obviously rotated thereby.

85 The means for rotatively supporting said rotative element 28 comprises a pair of tubular elements 29 and 30 which are held stationary in the bores 25 and 26 respectively, by means of set screws 32 and 32a, the inner ends of said elements 29 and 30 extending into recesses 33 and 34 respectively, of said rotative element 28. In view of this arrangement said element 28 is free to rotate on the ends of said tubular elements 29 and 30, the latter of course remaining stationary. Upon reference to Fig. 10 it will be noted that said rotative element 28 is provided with a radial slot 35 which flares outwardly toward the periphery of said element, and in Figs. 9 and 12 it will be observed that each of the tubular elements 29 and 30 are chambered as shown at 36 and 37, while the outer ends of said elements are slotted as indicated at 38 and 39, the chambers and slots in said tubular elements and the slot 35 in said rotative element 28 being coaxially arranged, and in communication with a longitudinal opening 40 in said block 22. As will presently appear, this arrangement permits the entrance of the wire into the respective slots and chambers of said tubular elements and said rotative element, by way of said opening 40. 110

115 The parts just described include the general mechanism for twisting the overlapping ends of the wire and it is apparent that the 120 rotation of the spur gear 5 places the said parts in operation. Now it becomes necessary to provide means for rotating said gear 5, and to this end I have adopted a crank 41, carried by one end of the shaft 42, which is journaled 125 130

in the side of the casing 43, as shown at 44, the inner end of said shaft being rotatively mounted in apertured bearing 45, depending from the top of said casing, while the extremity of said shaft, adjacent said bearing, is provided with a pinion 46, suitably splined thereto, as indicated at 47, in Fig. 4. The splined collar 48, (see Fig. 3) prevents the withdrawal of said shaft 42 during its operation. From the foregoing it is obvious that the manipulation of said crank 41 rotates said pinion 46, the movement of the latter being communicated to spur gear 5, and thence to the rotative element 28 journaled in the tubular elements 29 and 30, as aforesaid. At the same time the hubs 7 and 8, carried by the stub shaft 4, are rotating, and at pre-determined intervals the projections 9 of said hubs will encounter the oscillatory arms 15 and 16 and thus bring the cutters 19 and 19a into operative positions. At this time it is briefly pointed out that the rotation of said rotative element 28, through the intermediary of the spur gear 5 and pinion 46, creates the twist in the overlapping ends of the wire, while the cutters, operated by the oscillatory arms, clips off the undesired ends of the wire just subsequent to the twisting operation. The details of said operations will be taken up hereinafter.

The gripping mechanism, referred to in the objects of the invention, is mounted to rotate in the block 11, located at the left end of the base 1, in Figs. 3 and 6, said mechanism including a stub shaft 49, rotatively mounted in said block 11, one end of said shaft 49 being suitably affixed to head 50, carrying on operative lever 51, there being a pinned collar 52 affixed to said shaft 49 at the other side of said block 11 to maintain the parts in positive fixed relation. In said Fig. 3 it will be noted that said head 50 is provided with a shoulder 53 which abuts the stop pin 54, carried by said block 11 to limit the movement of said head. Said head 50 is further provided with a diametric bore 55, for the reception of a pointed pin 56 which is adjustable vertically by operating the set screw 57 and which is bound in its proper adjusted position by means of another setscrew 58. As shown in Figs. 3 and 4, said block 11 is provided with a ledge 59 for the reception of one strand of the wire to be twisted and in order to preclude the chances of undue wear, I propose to insert a wear pin 59a in said block, said pin being held in place by means of a set screw 60.

The automatic drop latch means referred to, comprises a latch member 61, which is pivotally supported between the ears 62 rising from said base 1, (see Figs. 4 and 6), as indicated at 63, the forward or head portion of said latch 61 being undercut, as shown at 64, to present a vertical surface extending in spaced parallel relation to the face of said

block 11 to maintain the wires in juxtaposed relation during the twisting operation. It will be noted that a laterally directed pin 65 extends across the upper rear edge of said latch 61, (see Fig. 6), and it is obvious that as the lever 51, of said gripping mechanism, is moved upwardly from the position shown in Fig. 3, said pin 65 is caused to bear against the edge of said latch 61 and cause the head portion to rise to permit the removal of the wire.

The means for tensioning or tightening the wire after placement around a box or bale, is rotatively mounted in a pillow block 66 which is preferably cast integral with said base 1 and positioned at the extreme right of said base, as shown in Fig. 6. Said block 66 is provided with a bore 67 for the reception of spindle 68, the latter having a star drum 69 affixed to one end and a hub portion 70 of an operating lever 71 at its other end, said hub portion 70 being free to rotate on said spindle 68. Interposed between said hub portion and an adjacent end face of said block 66 is a ratchet wheel 72 which is splined to said spindle 68. The purpose of said tensioning means is to tighten the wire that has previously been passed around a box or bale and as one end of the wire is clamped in the star drum 69, it becomes necessary to impart rotative movement to said drum by way of said spindle 68, but as the operating lever is adapted to be oscillated it becomes necessary to provide means for rotating said spindle when said lever is operated in one direction and for holding said spindle in a state of quiescence when said lever is raised from the position shown in Fig. 3 to a point for the commencement of its working or downward stroke. To this end it is proposed to provide spring-pressed dogs 73 and 74, the former being slidably arranged in a housing 75, preferably cast integral with said lever 71, while the latter is slidably arranged in a bored standard 76, see Figs. 2, 3 and 7. An inspection of said Fig. 3 will instantly reveal that when the lever 71 is elevated, said spring-pressed dog 73 rides over the teeth in said ratchet wheel 72 and as said hub portion 70 of said lever 71 is free to rotate on said spindle, no motion is imparted to the latter. During this operation said spring-pressed dog 74 intimately abuts said teeth of ratchet wheel 72 and holds the same stationary. When the lever 71 is lowered the dog 73 engages the teeth of the ratchet wheel and rotates the latter and the star drum affixed to said spindle 68.

The braking means referred to comprises a lever 77, pivotally supported by the side of the casing 43, as indicated at 78, the upper end of said lever extending through a slot 79 in said casing, (see Fig. 2), where it is bent to lie adjacent the handle 80, (see Fig. 4), for convenient operation. The other end

- of said lever 77 is provided with a projection 81 which is normally engaged within an opening 82 of said spur gear 5, the engagement being positive in view of the spring 83 having one end affixed to said lever, above its pivotal point, while its other extremity is anchored to a side wall of the casing 43 as indicated at 84 in Fig. 3. When the projection 81 is entered into said opening 82, the device 10 is inoperative and hence it is necessary to remove the aforesaid engagement before the handle 41 may be rotated. When the projection has been removed said gear 5 may be rotated and the projection glides along the 15 face thereof, but when the opening once more registers with said projection, the renewed engagement automatically stops the machine. Reference will be made to this feature hereinafter.
- 20 In using the device, the same is placed on a box or bale and one end of the wire is placed on the ledge 59 after the handle 51 of the head 50 has been slightly elevated, and as pointed out hereinbefore, said elevation of 25 said handle also raises the head of latch 61 so that the end portion of the wire may be expeditiously handled. When the handle is released it drops downwardly and the pointed pin 56 abuts the end portion of the wire 30 and at the same time the latch is dropped to the position shown in Fig. 4. The wire is now inserted through the opening 40 of the block 22 and into the radial slots of the barrels 29 and 30 and of the rotative element 27. 35 The wire is then carried around the box or bale, then beneath the cutaway portion in latch 61, thence into the slots in said barrels and rotative element 27 and finally caught behind the projections 85 of said star drum 40, as shown in Fig. 1.
- The star drum 69, hereinbefore referred to, is unique in construction, and is provided with a plurality of projections 85, which are arranged to define a plurality of peripheral 45 openings 86, (see Fig. 6) for the insertion of the wire as pointed out hereinbefore. In practice the end of the wire (see Fig. 1) is passed through convenient openings with its end protruding as shown, while the end portion of said wire abuts the faces of the contiguous projections and is clamped thereto during the tensioning operation about to be described.
- As pointed out hereinbefore, said lever 71 55 is adapted to impart an intermittent oscillatory movement to said spindle 68 and its affixed star drum 69 and it will be remembered that said lever was free to be elevated without affecting the ratchet wheel and that the 60 lowering of said lever imparted the necessary movement. Hence, when the end portion of the wire is caught between the projections 85 of said star drum 69, as aforesaid, the lever 71 is elevated until the detent 71a, (see Fig. 65 2) abuts the face portion 87 of the extension 88 of said standard 76, (see Figs. 2 and 7), said spring-pressed dog 73 riding over the teeth of the ratchet wheel 72. The aforesaid engagement between the detent 71a and the face portion 87 limits the elevated position of 70 said lever and as the same is lowered the dog 73 engages the ratchet wheel, rotating the star drum 69 and exerting a pull on the wire in the latter. The lever 71 is again elevated, but the ratchet wheel is locked from rotation 75 in view of the engagement by the spring-pressed dog 74 and when the lever is again lowered the continued rotation of the star drum further pulls on the wire and binds the enveloping portion thereof around the box. The aforesaid operation is continued until 80 sufficient tension is secured.
- Upon inspection of Figs. 2 and 7 it will be noted that the upper portion of said extension 88 is beveled, as indicated at 89 to afford a resting place for said lever 71 when the same is in the position illustrated. It is also pointed out that as the star drum is rotated the end portion of the wire shown in Fig. 1 encounters the projection or knob 90 which bends over said end portion and as the rotation continues the end portion contacts another knob 91 and is positioned as shown in Fig. 14. This arrangement firmly clamps 95 the wire and the bending of the ends thereof prevents injury to the operator's hands.
- During the tensioning operation the pull exerted on the end of the wire placed under the pointed pin 56, of the gripping mechanism, causes said pin to dig deeper into the 100 wire and thus the same is firmly clamped in that the greater the pull on the wire by the tensioning means, the greater the gripping action attending the pull.
- At present the twisting operation is about 105 to begin and it will be observed that the wire is properly tensioned around the box or bale and that the overlapping ends of said wire are arranged in two-strand relation within the slots of said barrels 29 and 30 and the radial slot of said rotative element 27. In other words, the overlapping ends of the wire are in juxtaposition within said slots and await the operation of the crank 41 to 110 twist the overlapping ends and shear off 115 the undesired portions of the wire.
- The lever 77 is operated to free the projection 81 from the opening 82 thus freeing the spur gear 5 and permitting its rotation when the crank 41 is turned. The rotation 120 of said gear 5 is in the direction of the arrows in Figs. 7 and 8, and this movement is imparted to said rotative element 28 in whose slot 35 the wire is positioned in a two strand, juxtaposed relation. It will be remembered that the wire is similarly positioned in the slots 38 and 39 of said barrels 29 and 30 and as this latter arrangement in said slots remains constant during the twisting operation, it is obvious that the torque applied to 125 130

the wire is due to the rotation of said element 28 and the slots 38 and 39, in which slots the ends of the wire are clinched. The number of twists to be imparted to the wire may be varied in accordance with the pre-determined ratio between the gears 5 and 28, but in the present instance said gear 5 makes one complete revolution during the twisting operation. During the twisting operation, the 10 projections 9 carried by hubs 7 and 8 swing through the recesses 92 in the oscillatory arms 14 and 15, (see Fig. 8), the rollers 93 establishing peripheral contact with the hubs 8 and 7. Eventually the projections 9 approach the rollers 93 and as they contact the same, said oscillatory arms 14 and 15 are rocked to the position indicated in Fig. 8, and the cutters descend to clip off the undesired ends of the wire, the cutter 19 cutting 20 off the end held by the gripping mechanism, while the cutter 19a clips off the end engaged in the star drum. After the projections 9 have operated the oscillatory arms, as aforesaid, and are back to the position shown in 25 Fig. 7, the rotative member 28 turns slightly and twists the ends of the cut wire, one up and one down, as shown in Fig. 13, and by this time the projection 81 in said lever 77 enters the opening 82 in said gear 5 and stops 30 the machine.

The device may be removed from the box or bale by elevating the handle 51 of the gripping mechanism which throws out the piece of wire gripped beneath the pin 56 and as the elevation of said handle also raises the latch 61, the device may be readily removed from said box, thus leaving the wire in proper twisted relation therearound. When wire is taken from a coil the handle 51 is not raised after the wire has been placed around the box or bale. The machine is taken away from the wire leaving the wire from the coil under the gripping pin 56 and before the machine is taken away the latch 61 is raised with the finger and the machine is pushed away from the wire leaving the end thereof from the coil under the pin 56 operated by handle 51. The operator places the device on another box or bale, raises the handle 51 and then 40 pulls the wire around said box, pulls the handle 51 that holds the pin 56 to slight pinch the wire and then the end of the wire that has been brought around the box back in the star drum 69 in the slot or opening 86. 45 When the star drum starts to tighten the wire it pulls the pin 56 against the stop pin 54 cutting an indentation into the wire during the tightening thereof. The end of the wire is placed around the box brought up to 50 the device again and slid underneath the latch 61.

As shown in Figs. 6 and 7, each of the oscillatory arms is provided with a spring 94 which extends from each of said arms to a 55 pin 95 rising from each of the standards 2

and 3. Said springs serve to return said oscillatory arms to their normal positions, shown in Fig. 7, after the passage of the projections 9.

As shown in Figs. 1 and 2 the crank 41 is positioned a good distance from the side of the casing to allow a clear space and to prevent the handle 96 from striking the box or bale. Said handle 96 is preferably covered with rubber or other resilient material 75 and the carrying handle 80 also has a covering of rubber as indicated at 97 in Figs. 4 and 5, a large stud screw 98 passing between the lugs 99 and 100. As shown in Fig. 1 a clear space is provided below the carrying handle 80 when the device is to be transported. In Fig. 14 the dotted lines 101 indicate that the knobs 90 and 91 may be undercut to receive the end portion of the wire. 85

It will, of course, be understood that the barrels and their associated parts may be substituted for others of varying dimensions when different sizes of wire are to be twisted. 90

The casing 43, hereinbefore referred to, is constructed of light-weight material and presents an open bottom whereby the same may be inserted over the mechanism, the bottom edge being provided with flanges, as 95 indicated at 102, in Figs. 3 and 4 for the reception of a series of screws 103 whereby said casing may be secured to the base 1. When the casing is inserted over the mechanism, the lever 77 is retracted to pass over the gear 100 5 until it registers with the opening 82 in said gear 5. The rear portion of said casing is inset as shown at 104 and is further recessed as shown at 105 to fit over the pillow block 66. The front portion of said casing 105 is also recessed, as shown at 106 to fit over the star drum 69, and as shown in Fig. 1 the medial front portion is slotted at 107 and 108 to permit the movement of the oscillatory arms 14 and 15, the slot 108 is continued laterally, as indicated at 109 to expose the major portion of the gripping mechanism and the latch. 113

From the foregoing it is apparent that I have developed a device which is compact 115 and which may be readily transported for applying and affixing the wire straps to a box or bale. In view of the provision of the novel gripping mechanism, and the star drum, associated with the tensioning means, the overlapping ends of the wire are maintained in proper two-strand relation within the twisting means and in view of the co-operation existing between the said gripping mechanism and the latch means, the device 120 may be bodily removed from the box after the twisting and severing operations. 125

While the present is a disclosure of the preferred embodiment of the invention, it is to be understood that the invention is not lim- 130

ited thereto, as various changes in the minor details of construction, proportion and arrangement of parts may be resorted to without departing from the spirit of the invention as defined in the appended claim.

I claim:

In a device of the character described, mechanism for gripping the end of a wire, means for tensioning the wire including a 10 rotatable star drum adapted to receive the other end of the wire, said means operating

to increase the clamping action of said gripping mechanism as the tension is increased, means for twisting the wire, rotative means for operating said twisting means, cutters operable by said rotative means and adapted 70 to sever the free ends of the twisted wire and latch means operated by said gripping mechanism to permit the removal of the wire from the twisting means.

In testimony whereof I affix my signature. 75
EARL D. TUBBS.
